(57) **CLAIM**

I claim the ornamental design for a retractable pet leash, as shown and described.

DESCRIPTION

FIG. 1 is a perspective view of the right side of a retractable pet leash.

FIG. 2 is a rear elevation view of the retractable pet leash illustrated in FIG. 1.

FIG. 3 is a front elevation view of the retractable pet leash illustrated in FIG. 1.

FIG. 4 is an elevation view of the right side of the retractable pet leash illustrated in FIG. 1.

FIG. 5 is an elevation view of the left side of the retractable pet leash illustrated in FIG. 1.

FIG. 6 is a top view of the retractable pet leash illustrated in FIG. 1; and,

FIG. 7 is a bottom view of the retractable pet leash illustrated in FIG. 1.

The broken lines shown in the figures represent portions of the retractable pet leash that form no part of the claimed design.
